S. M. UDALE

THERMOSTATIC MOLD CONTROL

Filed May 11, 1923

UNITED STATES PATENT OFFICE.

STANLEY M. UDALE, OF DETROIT, MICHIGAN, ASSIGNOR TO EARL HOLLEY, OF DETROIT, MICHIGAN.

THERMOSTATIC MOLD CONTROL.

Application filed May 11, 1923. Serial No. 638,154.

To all whom it may concern:

Be it known that I, STANLEY M. UDALE, a citizen of the United States, residing at 893 Lothrop Ave., Detroit, in the county of 5 Wayne and State of Michigan, have invented certain new and useful Improvements in Thermostatic Mold Controls, of which the following is a specification.

This invention relates to the thermostatic 10 control of the cooling fluid in a hollow permanent mold and specifically relates to the control of the cooling means shown in the co-pending application of De Forest W. Chandler, Serial No. 558,396, filed May 4, 15 1922.

In that application means are shown whereby air is blown through the mold during the interval between the ejection of the casting and the pouring of the next succeeding casting.

In the continuous operation of a series of molds arranged on a rotating table as shown in the above mentioned application it may happen that one mold receives more iron 25 than another, the result being that that mold becomes hotter than the remaining molds.

Under such circumstances the mold which is too hot should be given more cooling air than the molds which are not so hot and 30 this invention relates to thermostatic means for distributing the cooling air to those molds which are hotter than the others so that the molds will be all at a uniform temperature.

Figure I shows a cross sectional plan view through the device on the plane I—I of Figure II.

Figure II shows a cross sectional elevation through the plane II—II of Figure I.

Figure III is a fragmentary elevation of the air entrance to the mold.

Figure IV is a cross sectional elevation on the plane IV—IV in Figure I.

In Figures I and II, A is the thermostatic element, preferably consisting of two strips of dissimilar metal welded together. B is the control shaft supported in the side wall of the mold E. C is a throttle valve integral with the shaft B. D is the cover plate enclosing the valve C. A flanged pipe G flattened out at the end is bolted to the surface of the mold so that it lines up with the slotted passage F in the surface of the

mold. This passage F lines up with a corresponding slot through the valve C, when 55 the valve is in the open position.

The thermostatic element A is located in a rectangular opening J, the element A being partly within the hollow mold E and partly without. K is a cover to protect the 60 thermostat A from any molten metal which may splash from the top of the mold E. The cover K also provides an outlet for the air which enters from G through F C and finally issues through J. L is a cap screw 65 which forms an anchor for the thermostatic element A. M is a sector which is secured to the mold E. N is a pointer secured to the throttle shaft B adapted to indicate by its movement over the sector M. O is a cap 70 screw locating the sector M and also holding the cover K in place. The pointer N and the sector M indicate when the device is operating so that the operator knows when the supply of air through G is inadequate. 75 A V-shaped slot P in the circumference of the valve C permits a minimum amount of air to leak around the valve at all positions of the valve.

Operation: Air enters through G and F 80 and leaks around the valve C, through the V-shaped slot P into the hollow mold E. This air issues around the thermostatic element A and down through the cover K. As the temperature of the air issuing from K 85 rises the temperature responding elements turn the valve C. When the temperature E rises above 900° F. the temperature of the air rises to approximately 700° F. when the thermostatic element A has rotated the shaft 90 B so that the slightest increase puts the pipe G in free communication with the mold through the slot in the valve C. The moment the valve C opens a considerable quantity of air flows into the mold E which immediately reduces the temperature of the air issuing around A, through the slot J and to the atmosphere. This air flowing out at K immediately cools the thermostatic element A and the shaft B is rotated so as to 100 close the slot in the valve C and hence the temperature of the mold is kept within comparatively narrow limits, although no attempt is made to hold the temperature of the mold within very close limits as the process, in connection with which this device

2
is intended to operate, does not require close regulation. By arranging that the thermostatic element is never subjected to undue stresses, which is frequently the cause of 5 failure of the thermostatic element, the reliability of the device is increased.

What I claim is:

1. In a hollow mold, a cooling gas entrance, a valve located therein, a cooling 10 gas exit, a temperature responding element located therein, interconnecting means whereby the movement of the temperature controlling element operates the valve.
2. In a hollow mold, a cooling gas entrance, a valve located therein, a cooling gas 15 exit, a freely expanding temperature re-

sponding element located therein, interconnecting means whereby the movement of the temperature controlling elements operates the valve.

20

3. In a hollow mold, an air entrance there-
to and an exit therefrom, a valve controlling
the flow of cooling air through said
mold, a temperature responding element lo-
cated within said mold, interconnecting 25
means between the temperature responding
element and the valve whereby an increase
in temperature produces an increased flow
of cooling air through the said hollow mold.

25

In testimony whereof I affix my signa- 30
ture.

STANLEY M. UDALE.
